UNITED STATES PATENT OFFICE.

HENRY A. DAVIS, OF DAVENPORT, IOWA.

SELF-OILING LOOSE PULLEY.

No. 903,960.

Specification of Letters Patent. Patented Nov. 17, 1908.
Application filed June 8, 1907. Serial No. 378,017.

To all whom it may concern:

Be it known that I, HENRY A. DAVIS, a citizen of the United States of America, residing at Davenport, in the county of Scott and State of Iowa, have invented new and useful Improvements in Self-Oiling Loose Pulleys, of which the following is the specification.

My invention relates to improvements in loose pulleys in which a rim is secured to inwardly projecting hubs revolubly mounted upon a shaft; and the objects of my invention are, first, to provide simple and effective means for oiling such pulleys; second, to provide means for automatically returning the oil to the shaft after it has been carried away by centrifugal force; third, to provide simple and effective means to prevent the wear of a shaft upon which a loose pulley is mounted. I attain these objects by the mechanism illustrated in the accompanying drawings, in which

Figure I is a side elevation of the pulley showing inwardly projecting hub and the oiling block in dotted lines; Fig. II is a front elevation of one hub and of a portion of the shaft but shows the other hub and its attached side plate, and the rim and oiling block, in section on the line X—X of Fig. I; Fig. III is a side elevation showing in dotted lines the hub with the oiling block altered to form a ring; Fig. IV is a vertical cross section on the line X'—X' of Fig. III, but shows one hub in full lines instead of in section.

Similar letters refer to similar parts throughout the several views.

The rim A, is composed of hard pressed fiber or other suitable material and must be made impervious to oil either by the composition of the material used or by lining the inside of the rim with some substance impervious to oil.

Side plates H, are formed integral with the inwardly projecting hubs B, or with both the hubs and the rim, or suitably secured thereto and secured to the rim A, by screws I, or in any other suitable manner. The hubs B, are revolubly mounted upon the axle C. Each hub B, is provided on its inner surface with one or more longitudinal slots or channels, G, adjacent to and parallel with the surface of the shaft C, an annular channel K at the juncture of the hub and side plate, and also with oblique, radial

channels F, leading from the annular channels K, to connect with the oil chamber J, within the pulley. The oil block D, is revolubly mounted eccentrically upon the shaft C, intermediate the hubs B, and has its lower end weighted to keep it in position and its upper end extended so as to almost touch the inner side of the rim A. Channels E, are formed in the extended end of the oil block D, to conduct the oil to the channels G, in the hubs.

Referring to Figs. III and IV the extended end may be taken from the oil block D shown in Figs. I and II, and the interior of the oil block bored out to form a ring D', which will rest upon the interior of the rim A', and carry the oil from the rim to the axle, from which it will travel through the channels G', and F', and back to the ring D', along the inner face of the rim A'. 75

The principle of my invention is the use of centrifugal force to carry the oil away from the shaft and into contact with the oil block and the use of the oil block to conduct the oil back to the channels G and G', in 80 the hubs.

It is a well known fact that great difficulty is experienced in preventing loose pulleys from cutting out the axles upon which they revolve and the use of my invention secures 85 perfect oiling of such axles and thereby lengthens the life of such axles and the loose pulleys mounted thereon.

I have described two forms of oil block but it is obvious that various equivalent 90 means for conducting the oil from the rim back to the shaft may be used without departing from the principle of my invention.

It is designed to use a comparatively large quantity of oil in this pulley so that there 95 will be a continuous circulation of oil through the various ducts or channels; and when desired, the inner face of the rim may be sloped from each side toward the middle so that the centrifugal force will cause the 100 oil to collect at the middle of the rim. The oil necessary to operate this pulley may be put in when the pulley is mounted upon the axle and put together, or a suitable opening, as at P, may be provided for the admission 105 of oil, with a suitable stopper, Q, to close the opening.

In operation, the weighted end of the oil block D, keeps it practically stationary and when the ring D', is used, it rotates from 110

2
contact with the rim. Perforations as shown at O', may be provided in the ring to facilitate the passage of the oil to the shaft C'.

What I claim and desire to secure by Letters Patent, is

1. A loose pulley comprising a rim, and side plates and inwardly projecting hubs, formed integral with the side plates and spaced apart, having a plurality of longitudinal channels located in their inner surfaces parallel with axle openings in the hubs and in line with the axle, oblique radial channels extending from the inner ends of the longitudinal channels to the peripheries of the hubs, and annular channels in the inner surfaces of the hubs at the juncture of the longitudinal and oblique radial channels, and an eccentric oiling block loosely positioned between the inner ends of the hubs.
2. A loose pulley comprising a rim, and

side plates, and inwardly projecting hubs, formed integral with the side plates and spaced apart, having a plurality of longitudinal channels located in their inner surfaces parallel with axle openings in the hubs 25 and in line with the axle, oblique radial channels extending from the inner ends of the longitudinal channels to the peripheries of the hubs, and annular channels in the inner surfaces of the hubs at the juncture of 30 the longitudinal and oblique radial channels, and an eccentric oiling block in the form of a ring loosely positioned between the inner ends of the hubs and resting thereon and adapted to contact with the inner face of the 35 rim.

HENRY A. DAVIS.
